United States Patent

Des. 236,402
Patented Aug. 26, 1975

236,402

TABLE

Karl Lubke, Rheda, Westphalia, Germany, assignor to Lubke KG, Rheda, Westphalia, Germany

Filed Jan. 31, 1974, Ser. No. 438,389

Claims priority, application Germany July 31, 1973

Term of patent 7 years

Int. Cl. D6—03

U.S. Cl. D6—177

FIG. 1

FIG. 2

FIG. 3

FIG. 4

FIG. 1 is a perspective side view of a table showing my new design;

FIG. 2 is a perspective end view of the table shown in FIG. 1;

FIG. 3 is a top view; and

FIG. 4 is a bottom view of this table.

The appearance of the sides of the table not shown in the drawing is identical with the appearance of the sides shown in FIGS. 1 and 2.

I claim:

The ornamental design for a table, substantially as shown and described.
